SERVING TRAY UNIT

Alvin W. Levenhagen, Linesville, Pa., assignor to Molded Fiber Glass Tray Company, Linesville, Pa., a corporation of Pennsylvania

Filed Sept. 23, 1960, Ser. No. 62,248

Term of patent 14 years

(Cl. D44—10)

FIG. 1

FIG. 2

FIG. 3

FIG. 4

FIG. 5

FIG. 1 is a perspective view of a serving tray unit showing my new design, one of the removable elements being shown in separated relationship for illustrative purposes;

FIG. 2 is a longitudinal section of the composite unit; FIG. 3 is a perspective view thereof;

FIG. 4 is an enlarged fragmentary detail view of the inner corner of the removable element; and

FIG. 5 is a fragmentary detail view of the inner corner of the removable element taken at right angles to the view of FIG. 4.

I claim:

The ornamental design for a serving tray unit, as shown and described.
